HUGH S. KERR, OF PHILADELPHIA, PENNSYLVANIA, ASSIGNOR TO
ISRAEL FOSTER, OF SAME PLACE.

Design No. 4,651, dated February 14, 1871.

DESIGN FOR A CARPET-PATTERN.

The Schedule referred to in these Letters Patent and making part of the same.

HUGH S. KERR, of Philadelphia, county of Philadelphia, State of Pennsylvania, have invented or produced a Design for a Carpet-Pattern, of which the

wing is a specification.
The figure in the accompanying drawing represents a carpet-pattern to illustrate my design, main features of which are ornamented stripes *a a*, meeting at right angles, the ornamental square border arranged where the said stripes *a a* cross, the ornaments *d* between the stripes, the central ornament within the square tablet formed by the crossing stripes, and the ornamented square tablets *F* and *G*, bounded by the said stripes *a*, the said tablets being shown in the drawing.

Respective of the colors employed, I

claim—

The design for the ornamented square *b*, as illustrated.

2. The design for the ornaments *d* between the stripes *a*.
3. The design for the central ornament *e* within the square tablet formed by the crossing stripes *a*.
4. The design for the ornamental square tablets *F* and *G*, bounded by the said stripes *a*.
5. The design for the entire pattern, including the stripes *a*, border *b*, ornaments *d* and *e*, and tablets *F* and *G*.

In testimony whereof I have signed my name to this specification in the presence of two subscribing witnesses.

HUGH S. KERR.
